UNITED STATES PATENT OFFICE.

HENRY WARD DARROW, OF CHICAGO, ILLINOIS, ASSIGNOR, BY MESNE ASSIGNMENTS,
TO FRITZ MUSER, OF NEW YORK, N. Y.

DRIVING MECHANISM FOR WASHING-MACHINES.

1,207,142.

Specification of Letters Patent.

Patented Dec. 5, 1916.

Application filed December 7, 1908. Serial No. 466,337.

To all whom it may concern:

Be it known that I, HENRY WARD DARROW, a citizen of the United States, residing at Chicago, in the county of Cook and State of Illinois, have invented certain new and useful Improvements in Driving Mechanism for Washing-Machines, of which the following is a specification.

My invention relates in general to washing machines, and more particularly to driving mechanism for both rotating the washing cylinder and operating the clothes wringer.

In order to obviate the severe manual labor required to operate washing machines by hand, it is desirable to mount upon the machine a motor, preferably an electric one, and driving mechanism actuated by the motor, and to utilize the motor also for operating the clothes wringer, which convenience requires should be supported upon the machine in position to pass the washed articles therethrough as they are removed from the machine.

An objection to power-driven wringers as heretofore constructed is that the direction of rotation cannot be reversed, and hence articles when caught in the rollers are torn and the wringer must be dismantled to untangle them.

One of the objects of my invention is to provide a washing machine with a motor mounted beneath the machine without danger of injury from leaking water, the motor being supported by means which also contribute to the strength of the supporting frame of the machine.

Another object of my invention is to provide simple and efficient driving mechanism conveniently supported upon the end of the machine for operatively connecting the motor with the washing cylinder and with the wringer, and which may be readily controlled to actuate either the washing cylinder or the wringers.

A further object of my invention is to provide a clutch mechanism intermediate the driving means and the wringer for quickly reversing the rotation of the rollers in case garments become caught, thereby preventing tearing of the garments and avoiding dismounting the rollers to remove the garments.

A still further object of my invention is to provide a self contained, safe and easily

operable washing machine for household use, and the invention consists in devising, and in coöperatively combining, the component parts of a cylinder washing machine and of the driving mechanisms therefor, producing thereby a self contained, unitary machine, operable without any other accessories, except a source of electric current as it is available in households. Furthermore, in a washing machine, constructed according to my invention, the several mechanisms operating or driving its parts are designed and disposed in and between the parts of the machine, and housed in suitable casings, with the object in view to eliminate all danger of injury to the person using the machine, or to the clothing, and so that after switching on the electric current, the starting, operating and stopping of the machine requires merely the turning of a crank, provided with a handle located at a convenient point at the front end of the machine.

A washing machine, embodying the recited features of my invention, is illustrated in the accompanying drawings, wherein—

Figure 1 is an end elevation of my improved washing machine. Fig. 2 is a front elevation partly in section. Fig. 3 is a section on the line 3 of Fig. 1. Fig. 4 is a section on the line 4 of Fig. 1. Fig. 5 is a vertical section showing the lower part of the machine as viewed from a direction opposite to that of Fig. 1, this section being taken on the line 5 in Fig. 2 looking in the direction of the arrow, and Figs. 6 and 7 are detail sectional views taken on the correspondingly numbered lines in Fig. 3. Figs. 8 and 9 are details illustrating certain elements of the machine which may be identified by means of the reference numerals applied to them.

In the particular embodiment of my invention which I have chosen to illustrate and describe, the washing machine stands on four legs at the respective corners, each leg comprising two sections 15 and 16, secured together by means of the bolts 18 and the nuts 19. As shown in Fig. 5, the legs have an angular cross section and an upwardly projecting tongue 17 from the lower section 16 fits within the angular groove in the upper section 15.

Casters are provided at the lower ends of the corner posts as shown in Figs. 1 and 2. Inasmuch as these form no part of the in-

vention claimed herein they need not be described.

A horizontal brace 28 is connected to and supported by the two end legs 15. Above this is the end wall 29 of the washing machine tank. Above the horizontal brace 28 is another horizontal brace 30 extending across between the two legs 15, and above this is an extension 31 of the end wall. The reference numeral 32 indicates the front wall of the washing machine tank, within which is the rotatable washing drum 33.

The transverse brace 28 has a horizontal extension 34, on the under side of which is bolted the electric motor 35. The conductors 36 lead thereto from the hand switch 37, mounted on the end wall 31 of the washing machine tank. The conductors 38 lead from the screw socket 39 to the switch 37.

The motor shaft 40 carries a gear pinion 41. A stud 42 projects from the cross brace 28, to which it is attached by the riveted head 43. On this stud 42 is rotatably mounted the hub 44, from which the spokes 45 radiate to the internally geared rim 46, which is engaged by the pinion 41. An annular plate 46' is attached to the spokes 45 by means of screws. A bearing block 47 is mounted upon the end of the stud 42, being secured thereto by means of the two set screws 48. A shaft 49 carries a gear pinion 50, which meshes with the gear teeth 50' in the hub 44 of the main gear wheel 46. The shaft 49 has its end portion reduced in size as indicated by the reference numeral 51, and this is rotatably mounted in a corresponding socket in the block 47. A set screw 52, provided with a lock nut 53, is adapted to adjust the shaft 49 longitudinally. The block 47 has a flange 54 around the gear teeth 50.

The brace 30, which extends across the end of the machine, has a projecting bracket 55, to which an extension member 56 is attached by screws. Between the bracket 55 and the extension 56 is clamped a bushing 57 surrounding the shaft 49. A casing 58, having a row of holes 59, has its lower end resting on the bracket 55-56. The brace 61 is bolted to the corner of the machine, and a bracket 60 integral therewith projects up and ends in a cap 62, which is attached to and supports the upper end of the casing 58. Inside of the end wall 31 of the washing machine is a plate 63' from which a tubular extension 63 projects laterally, constituting a journal bearing for the shaft 64, to the end of which is fixed a gear pinion 65 by means of the pin 66. The collar 68 is loosely mounted on the shaft 49, and has the gear pinion 67 at one end thereof in mesh with the pinion 65. This collar 68 has ratchet or clutch teeth 69 adapted to be engaged by the opposed teeth 70 on the flanged sleeve 71. This sleeve 71 has sliding engage-

ment with the shaft 49, but is forced to rotate therewith by means of the key 71. The fork 72 (see Fig. 7) engages the sleeve 71 between the flanges at the ends thereof. The main part of the fork 72 has two rearwardly projecting members 80 between which is a slot 81. The shaft 73 lies in this slot 81, and is eccentrically mounted on the disk 74 journaled in the casing 58. Back of the disk 74 is a shoulder 75, to which are attached a crank 75' and a handle 76. The opposite end of the shaft 73 is journaled in the casing 58, the parts being held firmly in place by means of the coil spring 77 and the lock nut 78. The shaft 73 has an offset 80 at 79 corresponding to the eccentric mounting on the disk 74. Between the ends of the members 80 is fastened a plate 82, by means of bolts 83, the ends of the plate resting against the sides of the casing 58, and thus holding the fork 72 against rotation around the shaft 49. On the end of the shaft 64 is a gear wheel 84, which engages a train of gears mounted on the plate 85, that connects with the studs 86 to rotate the drum 33.

Within the cap plate 62, at the upper end of the casing 58, is an adjustable bushing 87, which engages the upper end of the shaft 49. The pinion 88 is loosely mounted on the shaft 49 against the washer 89. Another opposed pinion 90 is loosely mounted on the shaft 49 against the washer 91, which is supported by the collar 92, fixed on the shaft 49 by means of the set screw 93. Journaled in the bracket 60 is the short shaft 94 having a clutch 95 at its end, the purpose of which will be explained presently. On the opposite end of this shaft 94 is fixed a beveled gear wheel 96, which is in engagement with both the beveled gear pinions 88 and 90. The opposed ends of the beveled gear pinions 88 and 90 have clutch teeth 115 and 116, between which is the flanged collar 117 with opposed coacting clutch teeth at its ends. This collar 117 has non-rotatable but sliding engagement with the shaft 49 by means of the key 118. Within the flanges of the collar 117 is the fork 98, from which the two members 100 project having a slot 99 between them. There is a slot 97 in the casing 58, within which the members 100 are adapted to reciprocate; thus the fork 98 is held against rotation about the shaft 49. A disk 101, journaled in the casing 58, has a shoulder 102, from which extends a crank 107 with a handle 108 at its extremity. Eccentrically mounted in the disk 101 is a shaft 103, which has an offset 104 corresponding to the eccentricity of its mounting, the end of the shaft 103 beyond the offset 104 being journaled in the casing wall and the parts being held closely in place by means of the coil spring 105 and the lock nuts 106. The shaft 103 lies in the slot 99 of the fork 98.

The clutch 95 on the end of the shaft 94

is adapted to engage a transverse stud 111 on the end of the drive shaft 110 of the wringer 112. This wringer is adapted to be attached to the upper front edge of the 5 washing machine tank by means of the clamping jaws 113.

The above described mechanisms, devised to enable the rotation of the wringer rollers to be instantaneously reversed, is claimed 10 in my subdivisional application filed September 8th, 1916, Sr. No. 119,029.

A drip flange 114 is provided around the edge of the sleeve 34, beneath which the motor 35 is mounted. By this arrangement 15 water is prevented from running down through the motor.

Assuming that the clutch 69—70 is disconnected and that the crank 107 has the intermediate position shown in Fig. 2, whereby 20 the sliding collar 117 will be in an intermediate position with its clutches disengaged at both ends; then it will be apparent that when the electric motor 25 is set to running by properly throwing the switch 37, 25 the only effect will be to idly rotate the shaft 49 by means of the intermeshing gears 41 and 46. When it is desired to start the washing drum to rotating this is accomplished by throwing the crank 75'. This 30 causes the eccentric shaft 73 to push the clutch teeth 70 into engagement with the clutch teeth 69, and thus the rotation of the shaft 49 is communicated through the collar 71 to the gear pinion 68. This drives the 35 gear wheel 84, and thence through the intermediate train of gears mounted on the plate 85, the movement is communicated to the drum 33.

When it is desired to start the wringer 40 112, this can be accomplished by rotating the crank 107, which will cause the eccentric shaft 103 to shift the collar 117, thereby causing the clutch teeth at one end of the collar to engage the clutch teeth 115 or 116 45 on the respective gear pinions 88 or 90. Thus it will be seen that the rotation of the shaft 49 will be communicated through the collar 117 to one or the other of the gear pinions 88 and 90, thus rotating the wringer 50 rolls. The direction in which the wringer rolls are rotated will depend upon which clutch 115 or 116 is engaged by the collar 117, and this will depend upon the direction in which the crank 107 is turned from 55 its intermediate position shown in Fig. 2. Thus it will be seen that the wringer can be driven forward or backward or can be instantaneously stopped at will.

The transverse brace 30 in connection 60 with the parts 55, 56 and 57 forms a support for the shaft 49 and for the lower end of the gear casing 58. This brace 30 also stiffens the sheet metal end wall 29—31 at the end of the washing machine tank.

65 The gear protecting casing 58 acts as a

support for the two eccentric shafts 73 and 70 103 and also affords guiding means for the forks, which are reciprocated by these shafts. The holes 59 in the casing 58 facilitate oiling the gears.

I consider the reversible wringer driving mechanism a feature of decided importance. If garments become caught in the wringer 75 rolls, the latter may be quickly stopped and reversed, thus withdrawing the garments without tearing them or without making it necessary to dismantle the whole wringer in order to remove them.

The lower part 61 of the corner bracket 60—61—62 has a right angle cross section 80 fitting around the upper part of the corner post 15. The intermediate part 60 carries a journal bearing for the wringer driving shaft 94, and the top part 62 supports the casing 58 and also carries the adjustable 85 thrust bearing member 87 for the shaft 49.

The transverse brace 28—34 has a right angle cross section, which gives it great strength and at the same time affords a suitable support for the motor 35, the flanges 90 114 causing any drip water to fall down beside the motor instead of upon it.

I claim:

1. In a washing machine, corner posts, a horizontal brace connecting the two corner 95 posts at one end of the machine, said brace having a portion thereof in the form of a horizontal plate, a drip flange around the edge of said plate, a motor attached on the under side of the plate, washing mechanism, 100 and driving connections from the motor to said washing mechanism.

2. In a washing machine, corner posts, a substantially horizontal brace connecting 105 two corner posts at one end, said brace having a right angle cross section with one flange horizontal and the other flange vertical, a motor attached to the under side of the horizontal flange, a gear wheel rotatably supported on the vertical flange, driving 110 connections from the motor to the said gear wheel, washing mechanism, and driving connections from said gear wheel to said washing mechanism.

3. In a washing machine, the combination 115 of a supporting frame, a tank in the frame, and a cylinder rotatably mounted therein; an upwardly extending driving shaft journaled upon the supporting frame; a gear mounted thereon; means for rotating the 120 cylinder adapted to be actuated by the gear on the driving shaft; manually operable means controlling the operative connection between the gear on the driving shaft and the means for rotating the cylinder, a motor mounted beneath the machine upon the supporting frame, and operative connections between the motor and the driving shaft.

4. In a washing machine, corner posts, a 125 horizontal brace supported by two corner 130

posts at one end, a motor mounted on the under side of said brace, a stud projecting horizontally from the side of the brace, an intermediate gear wheel mounted on said 5 stud having a beveled gear pinion integral therewith, a block attached to the extremity of the stud, a shaft having one end journaled in said block, a beveled gear pinion fixed on said shaft in engagement with the 10 first mentioned beveled gear pinion, washing mechanism, and connections from the said shaft to drive the said washing mechanism.

5. In a washing machine, corner posts, a 15 horizontal brace attached to two end corner posts, a motor attached to the brace on the under side thereof, a stud projecting horizontally from the side of the brace, a block attached to the end of the stud by means 20 of set screws, a shaft having its end journaled in the said block, a gear pinion on said shaft, a projecting flange on the block around said gear pinion, intermediate gearing between the said motor and the said 25 gear pinion, washing mechanism, and driving connections from the said shaft to the said washing mechanism.

6. In a washing machine the combination 30 of a supporting frame, a tank in the frame, and a cylinder in the tank, rotatably mounted in the supporting frame; a casing affixed to the frame on one end of the tank, a driving shaft journaled in the casing, a motor mounted upon the supporting frame underneath the tank, operative connections between the motor and the driving shaft; a gear on the driving shaft, means for rotating the cylinder, adapted to be actuated by the gear on the driving shaft, and manu- 35 ally operable means for shifting the gear on the driving shaft in operative relation with the means for rotating the cylinder, and for controlling the rotation of the cylinder without stopping or reversing the motor.

40 7. In a washing machine, a corner post, a horizontal brace attached to said corner post at an intermediate point of the height thereof, a bracket projecting from the upper end of the corner post, a casing having 45 its ends supported by said brace and bracket, an intermediate driving shaft within said casing, a motor to rotate the driving shaft, washing mechanism, and gearing from the driving shaft to the washing mechanism.

55 8. In a washing machine, a corner post, a bracket having an angular cross section embracing the post at the upper end thereof, the extremity of said bracket having a journal bearing, an intermediate driving shaft 50 having its end mounted in said bearing, a motor to drive the shaft, washing mechanism, and driving connections from the shaft to said washing mechanism.

60 9. In a washing machine, a corner post, a bracket attached to the upper end of said

corner post, a cap at the end of said bracket, a casing having its upper end attached to the periphery of said cap, an intermediate driving shaft within the casing having its end journaled in said cap, washing mechanism, gearing from the shaft to the washing mechanism, a motor, and connections from the motor to drive said intermediate shaft. 70

10. In a washing machine comprising a tank and rotary cylinder therein, a corner post, a bracket attached to the upper end thereof, an intermediate driving shaft, means actuated by said shaft for rotating said cylinder, a bushing around the end of said shaft, said bushing being mounted in a 80 hole in the end of the said bracket, said bushing and the bracket having a screw threaded engagement whereby the bushing may be adjusted longitudinally, and said bushing having a shoulder over the end of 85 the shaft whereby it is adapted to act as a thrust bearing.

11. In a washing machine comprising a tank and rotary cylinder therein, a trans- 90 verse brace across the end of the machine, an intermediate driving shaft, means actuated by said shaft for rotating said cylinder, a bushing around said shaft, and an extension on the brace adapted to be attached thereto, said bushing being clamped between the brace and the extension. 95

12. In a washing machine, a supporting frame, a tank mounted therein, a rotary cylinder in the tank; a gear on the cylinder, a driving shaft extending upwardly across the end wall of the tank, and approximately at a right angle to the axis of the cylinder; a gear loosely mounted on the driving shaft, a manually operable clutch to engage the gear with the driving shaft; a shaft extending through the end wall of the tank, a gear on one end of the shaft, engaging with the gear on the driving shaft, and a driving gear on the other end of the shaft, operatively connected with the gear on the cylinder, substantially as herein shown and described. 105

13. In a washing machine comprising a tank and rotary cylinder therein, an intermediate driving shaft, a gear wheel loosely mounted thereon, means actuated by said gear wheel for rotating said cylinder, a clutch member adapted to reciprocate on the shaft and engage said gear wheel, a casing around the shaft, a disk rotatably mounted in the casing wall, a shaft projecting eccentrically from the disk and engaging a slot in said clutch member, said shaft having an offset at its end to correspond to the eccentric mounting at the other end, and a crank on the disk to rotate the same. 115

14. In a washing machine, the combina- 120 tion of a frame, a tank in the frame, a cylinder rotatably mounted therein; a motor 125 mounted on the frame underneath the tank, 130

a driving shaft journaled on the frame at an approximately right angle to the axis of the cylinder; means operatively connecting the motor with the driving shaft; means 5 on the cylinder, adapted to be engaged by a driving gear; a gear on the driving shaft, an intermediate gear, adapted to be actuated by the gear on the driving shaft, and engaging the means for rotating the cylinder, and manually operable mechanism for 10 operatively connecting the gear on the driving shaft with the intermediate gear, substantially as herein shown and described.

15. In a washing machine the combination of a frame, a tank in the frame, a cylinder rotatably mounted therein; means on the cylinder adapted to engage with driving gears for imparting rotatory motion thereto; a motor mounted on the frame underneath 15 the cylinder; a driving shaft, journaled in

the frame at an approximately right angle to the axis of the cylinder; means operatively connecting the motor with the driving shaft, a gear loosely mounted on the driving shaft, a manually operable clutching device for locking the gear to the driving shaft; a transmission shaft, journaled in the frame, and extending through the end wall of the tank; gears mounted thereon, one 25 engaging with the gear on the driving shaft and the other with the means on the cylinder for imparting rotatory motion thereto, substantially as herein shown and described. 30

In testimony whereof, I have subscribed my name.

HENRY WARD DARROW.
